UNITED STATES PATENT OFFICE.

GERALD DUMARS, OF NEW YORK, N. Y., ASSIGNOR OF ONE-HALF TO PAUL WING, OF WESTPORT, CONNECTICUT.

CHARACTER-TRANSFER DEVICE.

Application filed December 5, 1921. Serial No. 519,892.

To all whom it may concern:

Be it known that I, GERALD DUMARS, a citizen of the United States, and resident of New York city, in the county of New York and State of New York, have invented certain new and useful Improvements in Character-Transfer Devices, of which the following is a specification.

My invention relates to means for producing, composing, or building up, on a desired surface, characters, symbols, figures, designs or plans of any kind, by means of a predetermined pattern or outline. It has heretofore been customary to make up signs or 10 designs, by the use of ordinary stencils and like devices, but stencilled characters or figures have a crude appearance and lack a certain finish that is desirable in work of this class, and my present improvements 15 overcome these drawbacks as well as the shortcomings of other sign or design making devices as heretofore employed, and provides a very flexible means or system by 20 means of which the pattern or outlined 25 guide may be transferred to the desired surface, either in toto, or by sections from which the final work is built up, and such transferred parts or figures are then finished by hand work, using any of the ordinary 30 instruments and materials for such purpose. With these and other objects in view, my 35 inventions consist in the various novel and peculiar constructions and arrangements of the several different parts of the means, as well as the method of carrying out the work, all as hereinafter fully set forth and then 40 pointed out in the claims.

I have illustrated types of my inventions in the accompanying drawings, wherein:

Fig. 1, is a front face view of an intaglio pattern used in carrying out my invention, and shows a transparent sheet containing the letters of the alphabet and a set of numerals from 1 to 0.

Fig. 2, is an enlarged view of a portion of the pattern sheet shown in Fig. 1.

Fig. 3, is a cross-sectional view of the pattern-sheet, the section being taken on a plane indicated by line 3—3, in Fig. 2, with a crayon or bar of transfer material shown as being applied to the back face of the sheet to coat the outlines of the characters on the back.

Fig. 4, is a similar view to that of Fig. 3, with the coating-crayon removed and the

coated sheet applied to the surface upon which the figures or design is to be made.

Fig. 5, is a front-face view of the character or design bearing sheet or surface to which the transfer has been made from the pattern and on which the ultimate work is done.

Fig. 6, is a front-face view of a card bearing an intaglio figure of an animal-pattern and may form one of a set of cards having different characters, each card embodying my invention.

Fig. 7, is a front-face view of another intaglio pattern sheet of transparent material and bearing a series of characters usually found in Noah's ark toys.

Fig. 8, is a front-face view of a pattern sheet of transparent material bearing the figures or characters to be transferred, said figures being formed in suitable transfer substance or material on the back-face of the sheet, so as to read in positive relation from the front face thereof.

Referring to the drawings, in which like numerals of reference designate like parts throughout, 1 indicates a sheet of suitable flexible, transparent material, on the front face of which are formed a set of characters, symbols or figures 2, with continuous indented lines 3, producing intaglio figures or characters with respect to the front face of the sheet and in positive relation on said front-face. The depressions of the characters in outline are carried through the material of the sheet, so as to provide upon the back-face of the sheet, the same outline in relief 4, which stand up sharply from the surface of the back of the sheet so as to be sufficiently prominent to be readily smeared or coated with a transfer substance in the form of a powder, paste or bar, a crayon or bar of such material being shown at 5, in Fig. 3. The ordinary colored writing or marking sticks, such as those found on the market for lettering or drawing purposes, may be used for this purpose.

In the group of letters of the alphabet and the numerals shown on the pattern in Fig. 1, the characters are all of the same style and are alike in size as to the capital letters and the small ones, and they are arranged in horizontal lines in consecutive order, so as to enable the user to quickly select the desired character in building up the words or figures in the process of trans-

ferring the same. Near the base of each character and to one side, is arranged a horizontal guide line or mark 6, which is designed for aligning the characters on a certain line of the work or sign at the time of the transfer of the particular character, to its proper place in the work or sign, such as indicated on the placard 7, in Fig. 5. As a preliminary, the desired sign, plan or design which is to be produced on a surface, may first be roughly indicated thereon or laid off by pencil-marks in order to get the proper position and arrangement of the matter, when the transferring is being done. In other words, some means of guiding the location of the separate characters on the piece of work, is desirable, and this may be done by rough sketches. In order to produce the work desired, the pattern sheet may be placed face down and the raised characters on its back be then rubbed over with a stick 5, of transfer material, so that a quantity of such material will adhere to all the raised lines as indicated at 5^a, in Fig. 4, or the transfer material may be applied in any other suitable way, for example by pressing the raised characters down forcibly on an ordinary sheet of carbon paper used for making copies in typewriting. If it is desired to make a sign, for example, like that shown in part in Fig. 5, the pattern-sheet shown in Figs. 1 to 4, is utilized by first smearing transfer material 5^a, on all of the raised outlines on the back-face of the sheet, in the manner indicated in Fig. 4, and then the letter N is brought into proper position on the placard 7, and the stylus or pointed instrument 8, is passed along the grooves or intaglio of the letter with sufficient pressure thereon to cause the transfer material to mark the surface of the paper or sign surface 7. Then the letter E on the pattern sheet is positioned so as to bring it next to the N and on a line therewith by use of the guide-line 6, and the stylus is then operated to make the impression of the letter E, and this is followed by causing the letter W to be outlined on the sheet 7, as indicated at 5^b, which shows the double lines of the transfer or copy, which may afterwards be filled in with ink or a crayon in solid heavy lines like the two letters N and E, or all of the letters may be left un-filled like W, according to the character of lettering desired. As the pattern-sheet is of such a nature that it can be readily seen through, the proper position of any of the characters on the pattern can be readily located on the sign or placard 7, in forming the matter thereon, and the material being flexible, the transference of the characters is thereby greatly facilitated as a more intimate contact is thus obtained between the coated raised outlines and the surface on which they are to be transferred, and

this is an important advantage in my improvements.

In the arrangement shown in respect to the letters and numerals on the pattern-sheet, the indented lines are double and spaced apart some distance, and they are so formed that the point of the stylus or instrument 8, may be entered in the trough of the grooved lines and moved continuously through the same to complete the outlines of the particular letter being transferred, the requisite pressure being exerted on the stylus as it is so moved. The double line effect is shown in the work on sheet 7, at 5^b, and as before stated the letter may be left in this form after the lines have been touched up by hand work, or the space between the lines may be filled in as shown in the two letters N and E of the word New, on the sign. A pattern-sheet containing various symbols or a trade-mark, may be used to place certain characters on the sign, in addition to the lettering and numerals, such a symbol being shown at 15, on the sheet 7, in the form of a star, the outlines of which are in a single line, instead of double, and this device may be filled in or left as shown, according to the effect desired. Thus the outlines of the different characters on the pattern, may be made in double lines or single lines, as desired, and the lines may of course be varied as preferred. The pattern-sheet may contain various configurations and conventional designs which may be used at will in producing a sign with more or less artistic effect, and the same may be touched up by hand and elaborated by the operator, in order to embellish the work and make the same more ornate, and in this respect the pattern has the widest possible range, as to the various characters it may contain and the style of the same.

In Fig. 6, I show a small card 1^a, containing in intaglio the figure of a lion 9, which in outline is raised on the back of the card in the same way as described in reference to the letters in Figs. 1 to 4, and the card may form one of a set for the use of children, each card containing a different animal-figure, or kindred subjects. In Fig. 7, I show a pattern sheet or card 1^b, containing the figure of Noah's ark 10, and small figures of animals 11, which are supposed to be associated with the ark. These figures are made in intaglio with grooved lines which are raised on the back of the transparent sheet, in the same way as already described in reference to the previously described figures, and the characters or symbols are coated with transferring material and the pattern manipulated in the same way, so as to get on a sheet of paper or other suitable material, a transference of the various characters, which may then be treated in the way herein before set forth to finish the same.

In the modification shown in Fig. 8, the flexible, transparent sheet 1^c, has formed on its rear face the characters 12, here shown as letters of the alphabet, and they are made of transferring material, like for example the carbon compounds used on the carbon-sheets used for making copies in type-writing. The carbon composition being easily transferable, it will make a distinct impression on the blank sheet, by placing the pattern-sheet 1^c, thereon, in position to properly locate the place for the particular letter that is to be formed on the blank, and then rubbing the front face over the area covered by the particular letter and after making up the sign or placard in this way, the letters may be gone over and touched up and added to by hand work, in the manner already described. In the modification, as in the other form, the characters are in positive relation when read from the front-face of the pattern-sheet. In Fig. 8, there is also shown the blank sheet 7^a, on which the sign or design is to be built up or made, and part of the letter "b" is shown as transferred to or copied on the blank as at 13, by the rubbing process referred to. The pattern-sheet is turned up at one corner in order to show the transferred character on the blank.

As stated herein before, the pattern sheet is made of flexible and pliable material in order to better lend itself to transferring individual characters from the sheet to the blank, and the sheet is transparent in order to enable the user to locate the place for the particular part or character on the blank. The material of which the sheet is made should also be water-proof, so as to permit of frequent washing in order to keep it perfectly clean and to remove the smutty transferring substance which is smeared on the ridges of the characters on the back of the sheet for the transferring process. I use celluloid or any suitable cellulose material, or various vegetable or other parchment materials may be employed for the transparent or semi-transparent pattern sheet. In fact any well known material may be used for this purpose so long as it is flexible and will receive and retain the indented outlines of the characters. The outlines of the characters are shown as being in continuous lines so as to permit of an instrument 8, being readily and quickly run over the path of the lines and the material should be such as to withstand the pressure on the instrument which must be sufficient to make a clear and strong mark in thus transferring the outline to the blank, and of course the material should be durable enough to stand repeated operations thereon of the relatively sharp instrument referred to, in making the wanted design.

In addition to using the invention for producing certain designs and signs on the

blank surfaces, the pattern sheets may be used to teach children the shapes of letters of the alphabet and the numerals, and to instruct them in spelling words. The pattern design may be a map, or part of a map, each pattern sheet for example may contain a map of one of the States of the United States, and children may use the set in building up the complete map of the States and in this way made very familiar with the relative location of the different States. Of course, various pictures may be formed on the pattern-sheets, or parts of a picture, like the well known sectional picture-puzzle and the various parts assembled step by step, in composing the complete picture.

From the foregoing description, it will be seen that my improvements provide a very flexible means or system by means of which lettering, or various symbols or characters, or designs, plans, and maps or pictures of the most varied kind may be readily utilized in making up the desired article in the way of a design, sign, picture or what not, since I am able to employ patterns of practically any design and artistic nature and arrangement, and in this respect the scheme is practically unlimited in its range of use. It will also be noted that my improvement is peculiar in that it provides a self-contained or unitary pattern device, which is made ready for use by merely coating the raised characters on the back of the pattern-sheet. In using the form of pattern-sheet shown in Fig. 8, the transferred or copied character 13, is of course touched up by hand as hereinbefore stated in reference to the other form.

Having thus described my invention, what I claim and desire to secure by Letters Patent, is:

1. A device of the class described, comprising a transparent pattern-sheet having formed thereon a set of characters in positive relation as seen from the front-face of said sheet, and from which set characters are selected at will to make the desired composition on the transfer-surface, and the said characters being outlined upon the back-face of said sheet in suitable transfer material and being arranged to be placed normally against the surface to which the transfer is to be made and to cause the production on said surface of any of said characters by pressing or rubbing upon the front-face of a character on said sheet, the transparency of said pattern-sheet serving as means for enabling the operator to correctly position said pattern-sheet on said transfer-surface in order to transfer a character of said sheet to a desired or selected place on said transfer-surface.

2. A device of the class described, comprising a transparent pattern-sheet having formed thereon characters in positive rela-

- tion as seen from the front-face of said sheet, the said characters being adapted to be transferred to a subjacent surface by pressure from the front-face of said sheet, and guide-lines on said transparent pattern-sheet, adjacent said characters on said sheet for positioning said characters in alignment in transferring the same, the transparency of said pattern-sheet serving as means for
- 10 enabling the operator to correctly position said pattern-sheet on said transfer-surface in order to transfer a character of said sheet to a desired or selected place on said transfer-surface.
3. A device of the class described, comprising a transparent pattern-sheet having stylus-receiving intaglio characters formed on the front-face of said sheet in positive relation, and having the same characters formed on the rear-face of said sheet in raised outlines and constructed and arranged to permit of the same being coated or covered with suitable transfer or copying substance adapted to be transferred to the
- 25 desired surface by pressure upon any given character upon the front-face of said pattern-sheet, the transparency of said pattern-sheet serving as means for enabling the operator to correctly position said pattern-sheet on said transfer-surface in order to transfer a character of said sheet to a desired or selected place on said transfer-surface.
4. The method of causing the production of a wanted design, sign or picture, upon a surface, which consists in forming intaglio characters on a transparent pattern sheet in positive relation and forming the same characters in raised outlines upon the opposite side of said sheet, coating or covering said raised parts with suitable transferring or copying substance, then placing said pattern-sheet on the blank surface where the work is to be produced, and so positioning
- said pattern-sheet on said surface by means of the transparency of said sheet as to bring or locate a character of said pattern-sheet in a desired or selected place on said surface, exerting pressure on a character from the front-face of said pattern-sheet, to obtain transferred outlines on said work surface, then finishing the outlines on said work surface to complete the wanted design or picture.
5. A character transferring sheet for production of characters on a surface, consisting in a sheet having the transforming characters arranged upon the rear-side of said sheet and in relief in the reverse, the said reliefs being constructed and arranged to carry transfer substance and apply it to said surface against which it normally rests, when pressure is exerted over said character from the front side of said sheet.
6. A lettering or character forming sheet for the production of characters consisting of a thin flexible sheet of material having formed thereon intaglios of the characters on one side and reliefs of the characters on the opposite side directly opposite said intaglios, the said reliefs being constructed and arranged to carry transfer substance and apply it to a desired surface when pressure is exerted upon the said intaglio side.
7. A transfer sheet of transparent material having forms produced thereon to provide intaglio of the form on one side and a relief of the form on the other side opposite said intaglio, the said reliefs being constructed and arranged to carry transfer substance and apply it to a desired surface when pressure is exerted upon the said intaglio side.
- Signed at New York city, in the county of New York and State of New York, this thirtieth day of November, A. D. 1921.
- GERALD DUMARS.
